CHARLES F. MILLER, OF PITTSBURGH, PENNSYLVANIA, ASSIGNOR TO WESTINGHOUSE ELECTRIC & MANUFACTURING COMPANY, A CORPORATION OF PENNSYLVANIA.

UNDERFEED STOKER.

1,406,883.

Specification of Letters Patent. Patented Feb. 14, 1922.

Application filed May 21, 1917. Serial No. 169,932.

To all whom it may concern:

Be it known that I, CHARLES F. MILLER, a citizen of the United States, and a resident of Pittsburgh, in the county of Allegheny and State of Pennsylvania, have made a new and useful Invention in Underfeed Stokers, of which the following is a specification.

This invention relates to mechanical stokers and particularly to stokers operating on the underfeed principle, or those in which fuel is forced into the combustion chamber or furnace below the points at which air or forced draft is supplied, so that some of the volatile constituents of the fuel are distilled off and the fuel is partially or wholly converted into coke before mingling with the burning fuel within the combustion chamber.

An object of the invention is to produce a new and improved underfeed stoker in which improved means are employed for operating the fuel feeding and the refuse discharging mechanism.

A further object is to produce a furnace including new and improved means for feeding fuel into the furnace and for obtaining a substantially uniform fuel surface throughout the furnace area.

A further object is to produce means for underfeeding fuel into a furnace which distributes the fuel uniformly over the fuel bed support of the furnace and which operates with a minimum amount of resistance.

A further object is to produce a new and improved refuse discharge mechanism and new and improved means for operating the discharge mechanism.

A further object is to produce an underfeed furnace in which new and improved means are employed for distributing the air or forced draft to the fuel bed within the furnace.

These and other objects, which will be made apparent throughout the further description of the invention are attained by means of apparatus embodying the features herein described and illustrated in the drawings accompanying and forming a part hereof.

In the drawings, Fig. 1 is a longitudinal sectional view of a furnace embodying my invention.

Fig. 2 is a front view of the furnace illustrated in Fig. 1.

Fig. 3 is a fragmental longitudinal sectional view of a furnace and illustrates in detail the refuse discharge mechanism and the means employed for actuating it.

Fig. 4 illustrates in perspective different elements which compose a regulating device for the actuating means of the refuse discharging mechanism; one of the elements is shown in section for convenience of illustration.

Fig. 5 is a sectional perspective view of a portion of the actuating mechanism of fuel feeding plungers which form a part of the stoker illustrated.

Fig. 6 is a perspective end view of the apparatus shown in Fig. 5 and illustrates positions which different parts of the mechanism may assume after a shearing key forming a part of the mechanism, has been sheared by excessive strains on the mechanism.

Fig. 7 is a perspective view of a form of shearing key which may be employed in connection with the apparatus illustrated in Figs. 5 and 6.

Fig. 8 is a view partially in vertical section and partially in elevation of a portion of the actuating means of the refuse discharge mechanism.

The stoker illustrated as an embodiment of my invention includes an underfeed section shown as a retort 10 which extends across the front of the stoker and to which fuel is fed at points below the air or blast admission ports or passages, by means of fuel feeding plungers or rams 11 located at the front of the furnace and actuated by a fuel feeding mechanism which is also located at the front of the furnace. The fuel after entering the retort 10, is forced onto an over feed section, illustrated as comprising a series of alternately arranged stationary and reciprocating grate bars 12 and 12' which extend from the retort rearwardly to a refuse discharge mechanism 13 located between the grate bars and the bridge wall 14 of the furnace.

The retort 10 is formed by the cooperation of so called retort bodies 15, an inclined table 16 and the forward ends of the stationary and reciprocating grate bars. The bodies 15 are formed in relatively short sections, are mounted on the inclined table 16, and each includes a fuel hopper 17, located

at the front of the furnace, a guide or passageway in which one of the rams 11 operates, and an air box 18, the rear wall of which forms the front wall of the retort 10. The guideway in which the plunger 11 operates is located below the hopper 17 and forms a means of communication between the hopper and the retort.

The inclined table forms in effect the floor 10 of the retort 10 and its forward edge is mounted on a box section 19, which extends throughout the width of the furnace and forms the lower portion of the front wall of the stoker. The rear edge of the inclined 15 table is mounted on a support bar, shown as an angle bar 20, which extends across the furnace, and is mounted at intermediate points, on pedestals 21. The pedestals are shown mounted on frame members 22, which 20 are suitably spaced throughout the width of the furnace and are in turn mounted on suitable supports such as beams 22^a.

The grate bars 12 and 12' are shown inclined downwardly toward the rear of the 25 furnace. Each bar is mounted at its upper end on a support plate or member 21^a, which extends from one side-wall to the other of the furnace, and is supported at intermediate points on the pedestals 21. The lower 30 ends of the grate bars are shown supported on a twyer box 24, which extends at right angles to the grate bars and is mounted on the frame members 22. The twyer box is provided in its grate bar supporting face 35 with air delivery ports or passages 24^a, which are adapted to communicate with air admission ports formed in lower ends of the hollow bars 12 or 12'.

Air under pressure is delivered to the 40 twyer box 24 through a passage 25, which is formed below the fuel supporting surface of the stoker by means of plates 26 and 26^a mounted on the frame members 22, and consequently spaced apart by these members. 45 The upper series of plates 26 divides the space below the fuel supporting surface of the stoker into what may be termed the primary air chamber 25 and a secondary air chamber 25^a, the latter being located immediately below the grate bars 12 and 12' and the inclined table 16. Blast or air under pressure is delivered to the chamber 25 through a conduit 27, and may be controlled by means of a damper or valve 28 located 50 within the chamber 25 and actuated from the front of the furnace by means of a rod 29 and a hand wheel 29^a.

Substantially all of the air delivered to the combustion chamber of the furnace or 55 stoker first passes through the grate bars 12 and 12'. Each grate bar is hollow, is provided on its fuel supporting faces with transversely extending serrations located in stepped relation, and its interior air passage 60 is so formed that a portion of the air de-

livered to each bar is discharged into the chamber 25^a through a port or passage 30 formed in the lower face of the bar and located intermediate its ends. A portion of the air traversing each bar is also discharged 70 into the chamber 25^a through ports 31, formed in the bottom face and located immediately adjacent to or near the upper end of the bar. The upper end face of each grate bar is provided with a series of twyer 75 openings or ports 32, which discharge air into the retort 10 substantially at right angles to the direction of travel of fuel issuing from the retort.

With this arrangement of grate bars the 80 bars are cooled by the incoming air and the incoming air is preheated before it is delivered to the fuel on the fuel supporting surfaces. By providing a port 30 in each grate bar I reduce the cross-sectional area 85 of the grate bar and at the same time supply enough air through the bars to support combustion within the combustion chamber and to thoroughly cool the bars. It will, of course, be understood that the rearward 90 portion of each bar is subjected to the greatest heat and consequently it is desirable to expose that portion of the bar not only to the coolest air but also to the largest volume of flow of air. With the arrangement illustrated the incoming air is delivered to the lower ends of the grate bars and substantially all of the air entering the furnace traverses the lower ends of the grate bars. The front portions of the grate 100 bars are subjected to less heat, since they are more thoroughly protected by green or partially burned fuel, and they consequently require less cooling. For this reason it is permissible to discharge a portion of the 105 cooling air from the grate bars at intermediate points and thereby render it possible to reduce the average cross-section of the bars and consequently their weight.

The preheated air discharged from the 110 ports 30 and 31 is delivered to the fuel bed through passages formed between the bars 12 and 12', it being understood that the bars are suitably spaced to permit air to pass upwardly from the chamber 25^a into the fuel 115 bed. This preheated air, by being exposed to the heated grate bars, further cools the bars and consequently takes up additional heat from the bars as it enters the combustion chamber. In addition to this, the inclined table 16 is subjected to the cooling action of the air in the chamber 25^a. The temperature of this air is considerably less than the air delivered through the ports 32, since it has not been subjected to the same 120 amount of heating. Air is also delivered from the chamber 25^a to the twyer box 18 located in the retort bodies 15.

Each retort body contains a section of the twyer box and the box extends across the 130

front of the furnace and communicates with the chamber 25^a through passages 33, which extend downwardly through the bodies 15 and register with suitably located ports 5 formed in the inclined table 16. For convenience of manufacture, and also for lightness of structure, and for the additional purpose of cooling each body as much as possible and at the same time for imparting a 10 maximum amount of heat to the air delivered to the incoming fuel, I preferably provide each body portion with two lateral channels, each of which is so arranged that it cooperates with the corresponding channel 15 in an adjacent body portion and forms with it one of the air conducting passages 33. These passages, together with the air box 18, form arches through which fuel is fed by the rams 11 into the furnace or into the 20 retort 10. The twyer box 18 is provided with a series of ports 34, which extend across the front of the furnace and discharge air from the box across the mouth of the retort, and approximately at an angle to the 25 line of travel of the fuel issuing from the retort.

As illustrated, the stationary grate bars 12 are held against longitudinal movement by means of lugs 12^a and 12^b, the former of 30 which engages a rear edge of the plate 21^a, whereas the latter engages a shoulder formed on the forward edge of the twyer box 24. With such an arrangement, the stationary bars are capable of lateral motion 35 and may be readily removed from their supporting members, but are firmly held against longitudinal motion.

The moving bars are adapted to reciprocate longitudinally and at the same time to 40 move in such a way that their lower ends are periodically projected above the plane defined by the fuel supporting surface of the stationary grate bars. This is accomplished in the stoker illustrated by providing the 45 lower ends of the bars with supporting faces which are inclined upwardly toward the rear of the furnace and by forming the grate bar supporting face of the twyer box 24 so that it is inclined at a corresponding angle. 50 With this arrangement the reciprocating motion of the grate bars causes their lower ends to move upwardly and to attain the highest position when the bars are at the end of their rearward stroke. As illustrated, the upper end of each bar is so formed that its upper supporting face, which 55 engages the plate 21^a, is substantially horizontal when the bars are in their normal positions.

60 The moving grate bars 12' are actuated by means of a rocker bar 36, which is supported in suitable bearings formed in the pedestals 21 and which extends from one side to the other of the furnace. The rocker bar is 65 provided with a downwardly extending arm

37, which is operatively connected by means of a link 38 and an adjustable lost motion connection to an oscillating lever 39, forming a part of the stoker drive mechanism.

The lost motion connection consists of a 70 rod 40^a, a fixed collar 40 mounted on the rod and an adjustable collar formed on a sleeve nut 41, which is screwed on to the end of the rod 40^a. The fixed collar and the adjustable collar are adapted to engage the arm 75 39, or a lug provided on it, and to impart motion to the rocker-bar 36.

The stoker drive mechanism illustrated is standardized so that its parts may be duplicated in large stokers. In this connection 80 attention is called to the fact that the retort bodies 15 are standard and interchangeable; the moving and stationary grate bars 12 and 12' are each of standard construction; and the table 16 and member 19 may be divided 85 into standard lengths, consequently a stoker of substantially any desired width may be built up by assembling the desired number of standard parts.

In Fig. 2 of the drawings I have illustrated 90 a stoker of standard width for a boiler of a certain capacity, and it will be seen that this stoker includes six assembled body portions. In this figure I have illustrated a drive mechanism which will serve 95 the stoker illustrated and which consists of two standard drive mechanisms each adapted to serve that portion of the stoker including three body portions.

Each standard drive mechanism includes 100 a shaft 42, which is journaled in brackets formed on or secured to the front of the front wall of the stoker. The arm 39, which imparts oscillatory motion to the rocker bar 36, is keyed or otherwise rigidly mounted on 105 the shaft 42.

The connecting rod 46 is operatively connected to a crank arm 48, which is mounted on a crank shaft 49. It will be apparent that the crank shaft 49 is adapted to transmit power to each standard drive mechanism and that it is therefore provided with 110 two cranks 48. The shaft 49 may be a continuously rotating shaft and may be driven by a motor or engine 50.

The fuel rams 11 are periodically reciprocated by the shafts 42, it being understood that each shaft 42 of the stoker illustrated in Fig. 2 operates three fuel rams. The operative connection between each ram 11 and its operating shaft 42 is such that it may be broken without injury to the ram, the driving mechanism, or any of the stoker parts, in case the ram encounters abnormal resistance to motion. In the apparatus illustrated this is accomplished by providing a two-part gear hereinafter more fully described which is mounted on the operating shaft 42 and meshes with a rack 11^a, formed on the ram 11. The two parts of the gear 125 130

are adapted to be secured together by what may be termed a shearing key, which is of sufficient strength to transmit normal strains, but is so designed that it will shear 5 when subjected to abnormal strains, and thereby release the rack engaging portion of the gear from the driving shaft 42. In Figs. 5 and 6, I have illustrated the two part gear employed for driving one of the 10 rams 11. Each gear consists of an inner or hub portion 51, which may be keyed or otherwise rigidly mounted on the shaft 42, and an outer or rack engaging portion 52, which surrounds the hub portion 51 and is 15 adapted to be rigidly locked to it by means of a shearing key 53. It will, of course, be understood that for convenience of assembling, the outer portions 52 may, and preferably will be formed in semi-annular segments, as illustrated in Figs. 5 and 6, and that one segment only need be provided with gear teeth, for engaging rack 11^a. The 20 number of teeth on the toothed segment will depend upon the desired throw of the ram 25 11, and the angle of oscillation of the shaft 42, and the diameter of the segment. It will also be understood that any desired means may be employed for preventing lateral motion of the outer portion of the gear, with 30 relation to the hub portion, after the shearing key has been severed by undue strain. I have illustrated the hub portion 51 as provided with a key seat 54 which may be of hardened or specially tempered metal and 35 which is adapted to receive the shearing key 53. The portion 52 is also provided with a key seat or way which operates with the seat 54 in receiving the key 53. The key, as 40 illustrated in Fig. 7, is bifurcated at the end adapted to project beyond the key ways and is so arranged that a projecting tip 53' is formed on each portion of the severed key by means of which the separate portions 45 may be removed from the ways. This arrangement of two part gear and shearing key is an improvement over similar devices adapted to fail and to thereby prevent the parts from being subject to breaking strains, since the strains imparted to the shearing 50 key do not vary for different positions of the gear, consequently an abnormal resistance to motion, encountered by the ram at any point in its stroke will shear the pin, and the position of the pin is not a determining factor in the amount of stress to 55 which it is subjected.

The shafts 42 also actuate the refuse discharge mechanism 13. As illustrated, the mechanism 13 includes two dump grate mechanisms, each actuated by one of the shafts 42 and serving one half the stoker, or a portion made up of three retort bodies 15 and cooperating grate bars 12 and 12', ram 11, etc. Each dump mechanism illustrated

is of the type known as the double leaf dump 65 and includes two tilting dump grates 55 and 56. The grate 55 is located immediately adjacent to the lower ends of the inclined grate bars and so arranged that its rear edge is adapted to move downwardly when the grate 70 is tilted for the purpose of dumping refuse into the ash pit. Each rear tilting grate 56 is mounted adjacent to the bridge wall 14, so that its forward edge moves downwardly when the grate is tilted for the purpose of dis- 75 charging into the ash pit. With this arrangement the grates 55 and 56 cooperate in bridging the space between the grate bars 12, 12' and the bridge wall. As illustrated, each of the dump grates 55 and 56 is so formed 80 that they cooperate to produce a crushing action on the clinker or other material supported on them as they are moved to the dumping position. This is accomplished by pivoting each grate at a point intermediate 85 its forward and rear edges so that one edge will move upwardly and inwardly an appreciable distance as the other edge moves downwardly and outwardly to accomplish the dumping. Referring to the grate 55, it 90 will be seen that it is pivoted at a point intermediate its forward and rear edges but that the trunnion about which it turns is located nearer the forward edge than the rear edge. The forward edge is also provided 95 with an upwardly projecting jaw 57, which extends transversely of the furnace and which cooperates with a similar jaw 58 formed on the grate 56 in crushing the material located on or above the dump grates 100 at the time of dumping.

In Fig. 3, I have illustrated one dump grate mechanism in section and moved to the dumping position, whereas the other dump grate mechanism, serving the farther half of 105 the stoker, is shown—so far as possible—in elevation and is the normal or “closed” position. In order to prevent the dump grate from burning out and also to prevent the burning off of the crushing jaws 57 and 58, each dump grate is hollow or is provided 110 with cooling passages through which air may be circulated while the grates are in the closed position. As illustrated, each dump grate is provided with a passage 59 which 115 extends from the jaw edge of the grate substantially to its downwardly moving edge, and air is delivered to this passage through a port 60 which registers with a port 61 when the grate is in a closed position. The passages 59 are both open so that ash or solid material will be discharged from them either by the force of the blast passing through them, or by gravity when the grates are moved to the dumping position. The port 120 61, adapted to supply air to the grate 55, is located in the rear wall of the air box 24, whereas the port 61' supplying air to the op-

positively disposed grate 56 is located in the forward wall of an air box 62, which is mounted on or is built into the bridge wall 14.

In order to prevent the unnecessary discharge of air from the ports 61, during the dumping period, but primarily to prevent the ash or solid material from falling into the space between each grate and the adjacent air box during the dumping period, each 5 grate is provided with a depending apron 63 which is adapted to close the port 61 and prevent the passage of ash or solid material between the grate and the adjacent air box. As 10 illustrated, each apron 63 is located along the jaw edge of the grate and the apron and the contiguous face of the jaw is curved, the center of curvature being at the pivot point of the grate. With such an arrangement each apron forms a valve for the port 61 and a 15 gate to prevent ash from lodging in behind the grate. For the purpose of burning out all the carbon contained in the ash supported on the grates prior to dumping, I have provided a port in the air passage 25 for the 20 purpose of delivering blast to the ash pit or to the space below the dump grates. This port is controlled by a valve 26^b, which is in turn controlled by a rod 26^c which projects through the front of the furnace. 25 The grates 55 and 56 are operated by the shaft 42. Each pair of grates is operatively connected to its operating shaft by means of a lever 64 rigidly mounted on the shaft, an adjustable lost motion connection 65, a bell 30 crank 66, a rack 67, a gear 68 meshing with the rack, and a dumping lever and crank, which are actuated by the gear 68. The bell crank 66 is pivotally mounted on a bracket at the front of the furnace and transmits motion to the rack 67 by means of a link 69 and a rod 70, the rod projecting through the front of the furnace. The rack 67 is located below the dump grates but out of the line of discharge into the ash pit. The rear grate 56 35 is actuated by means of a lever 71 and a link 72. The lever 71 is illustrated as being keyed on a shaft 73 on which the gear 68 is mounted, and the link 72 is pivotally connected to an arm 74, which may be mounted on or otherwise rigidly secured to the 40 grate 56. The forward grate 55 is operated by a corresponding arrangement of links and levers including the lever 75, mounted on the shaft 73, a link 76 and a lever 77. The 45 levers 71 and 75 are so mounted on the shaft 73 that a turning of the gear 68 will simultaneously move both grates 55 and 56. In Fig. 1, the grates are shown in the closed position, and the corresponding position of the 50 rack, the gear and the levers 71 and 75 are clearly illustrated. In moving the grates to the dumping position, the rack 67 is moved toward the front of the furnace, thereby imparting a clockwise motion to the gear 68 and simultaneously moving both the levers 71

and 75 in a clockwise direction. In Fig. 3 the actuating members of the grates shown in section are indicated by reference numerals, whereas the actuating members of the other dump grate mechanism are unnumbered; 70 this is done for the purpose of avoiding confusion, and for indicating the positions assumed by the levers 71 and 75 when the grates are fully open.

The lost motion connection 65 includes oppositely threaded screws 80 and 81, which are rigidly mounted on a hub portion. The hub is provided with an operating hand wheel 83 and also with a cylindrical guide and abutment portion 84, which surrounds 80 the screws 80 and 81. A sleeve nut 85 is threaded on to the screw 80 and a sleeve 85^a is threaded on to the screw 81. These sleeve nuts telescope with the cylindrical guide 84 and are adapted to be moved to different 85 longitudinal positions, relatively to the guide, by a turning of the hub. A combination trunnion and block 86 is slidably mounted on the sleeve nut 85 and is adapted to form the operative connection between 90 the adjustable connection member 65 and the lever 64. For this reason it is provided with a trunnion 86^a which is journaled in a boss formed on the outer end of the lever 64. The longitudinal motion of the block 86 along 95 the sleeve 85 is limited by the upper end of the member 84 and a collar formed on the upper end of the sleeve 85. The sleeve 85 is prevented from turning about the screw 80 by the cooperation of a set screw 87 mounted on the block 86 and a slot 88 formed in the sleeve 85. The adjustable connection 65 is similarly connected to one arm of the bell crank 66 by means of a combination trunnion and block 86^c, which is slidably mounted on the sleeve nut 85^a. Turning the hand wheel 83 in one direction moves both the sleeve nuts outwardly and thereby increases the free motion of both of the blocks 86 and 86^c along their mounting sleeve nuts. A turning of the hand wheel in the other direction 100 decreases the free motion of the blocks 86 and 86^c and when the sleeves 85 and 85^a reach their innermost position, with relation to the member 84, the blocks 86 and 86^c are 105 locked against relative longitudinal motion and the entire motion of the lever 64 is imparted to the bell crank 66.

With this arrangement the dump grates may be moved from the closed to the fully 110 open position, or they may be moved from the closed to any intermediate position. When it is desired to retain the grates in the closed position, the hand wheel 83 is turned so that no opening motion will be 115 imparted by the adjustable connection 65 to a bell crank 66. In Fig. 1, I have shown the member 84 with the sleeve nuts extended to such positions that no motion is imparted to the dump grates. In Fig. 3, the adjust- 120

able connection 65 is shown adjusted to transmit maximum motion to the dump plates. In order that the dump grates will not swing from the closed to the dumping position, I have substantially balanced each grate about its trunnion, and in addition to this, I have so arranged the links cooperating with the levers 71 and 75 that there is no tendency for unbalanced forces to swing the grates from the fully closed to the fully open position. By a reference to Fig. 1, it will be apparent that the levers 71 and 75 are so positioned that each is substantially at dead center, so far as the connecting links are concerned, when the grates are in the fully closed position and consequently neither grate can impart a turning movement to the gear 68, but it must remain locked in the closed position until the rack 20 is shifted through the agency of the connecting device 65.

The operation of the stoker illustrated is as follows: The shaft 49 is driven at a relatively slow speed; the oscillations of the shafts 42 connected thereto are therefore relatively slow, resulting in an appreciable interval of time for each oscillation. The cranks 48 are so positioned on the shaft 49 that one shaft 42, of the stoker illustrated, 30 is moving through the fuel feeding portion of its stroke while the other shaft 42 is withdrawing the fuel plungers. The shaft 49 is consequently subjected to continual resistance, since one shaft 42 takes up the load occasioned by forcing fuel into the furnace as soon as the other is relieved of this load. The rams force fuel from the hoppers into the retort 10 and, after the retort is full, the fuel is crowded out of the 40 retort on to the grate bars 12 and 12'. The inclination of the grate bars and the reciprocation of the moving bars 12' cause the fuel to move downwardly across the bars and to be eventually deposited on the dump 45 grates. The reciprocation of the grate bars 12' not only augments the downward travel of the fuel, but tends to break up the fuel bed and to maintain a substantially constant distribution of the fuel over the fuel supporting surfaces. As previously stated, the 50 connection 65 may be adjusted to impart a full opening and closing motion to the dump grates or it may be adjusted to impart an intermediate opening motion to the grates. 55 This latter adjustment may be a relatively permanent one and if employed will accomplish a continuous discharge of ash from the furnace. Under ordinary operating conditions the dump grates will be opened periodically, remaining fully closed between dumping periods. The dumping operation will then consist in adjusting the connection 65, as illustrated in Fig. 3, and maintaining this adjustment until the arm 75 has completed one cycle in which it has moved the

grates from the closed to the fully open and then back to the closed position. After this is accomplished the adjustment of the connection will be changed to that illustrated in Fig. 1, and the shaft 42 will then impart no motion to the grates or their operating mechanisms.

All the air entering the combustion chamber of the stoker is first delivered to the primary air chamber 25. The inlet port to this chamber is controlled by the valve 28, and the valve may be adjusted to meet the desired conditions of blast. The air periodically delivered to the ash pit and through the valve 26 is not materially preheated before entering the fuel bed, but with this exception all air entering the fuel bed is first employed in cooling a fuel supporting member and consequently is preheated. The preheating is advantageous for two reasons; first the air delivered to the green fuel as it leaves the retort 10 should be hot enough to aid in the distillation of the fuel and second, the more exposed parts of the furnace should be more effectively cooled than parts protected by an adequate bed of green or fresh fuel. The air delivered to the twyer openings along the sides of the retort is therefore subjected to maximum heating, whereas the large volume of air delivered to other portions of the fuel bed is subjected to less preheating in order that it may be more effectively employed in cooling the more exposed fuel supporting members. The air delivered to the dump grates 55 and 56 is delivered from the chamber 25, it being understood that the air box 62 preferably communicates with the chamber 25.

The air passing through the entire length of the grates 12 and 12' is delivered to the ports 31, whereas the remainder of the air passing through the grate bars is delivered to the chamber 25. A portion of this air is delivered directly to the fuel bed between the grates 12 and 12', and the remainder is further heated in its passage to the twyer box 18 and is delivered to the tuyers 34.

In Fig. 1, I have shown air delivery ports 71* in the front wall of the stoker for delivering the preheated air to the combustion chamber above the fuel bed. These ports receive air from the air box 72*, through a port which may be controlled from the front of the furnace by a valve 73*.

While I have described but one embodiment of my invention, it will be apparent that various changes, modifications, additions, omissions and substitutions may be made in the apparatus illustrated without departing from the spirit and scope of the invention, as set forth by the appended claims.

What I claim is:

1. In combination in a stoker, a fuel-feed mechanism, a retort extending across the

- front of the stoker, alternate movable and stationary grate bars inclined rearwardly from the retort, a discharge mechanism at the rear of the grate bars, means for actuating the fuel feed mechanism, the movable grate bars and the discharge mechanism uniformly, and means included in the actuating means for imparting a variable relative motion to the discharge mechanism.
- 10 2. In combination in a stoker, a retort extending across the front of the stoker, alternate stationary and movable grate bars having their forward ends supported by the bottom of the retort and arranged to 15 form a wall of said retort and said bars extending downwardly toward the rear of the furnace, fuel feeding rams spaced along the retort and so located that fuel is fed into the retort below the surface of the fuel maintained therein, a dump grate mechanism 20 located adjacent to the lower edge of the grate bars, a driving mechanism for actuating said rams, movable grate bars and the dump grate mechanism, and means carried 25 by the drive mechanism for imparting an adjustable range of motion to the dump grate mechanism during the normal operation of the rams and grate bars.
3. In combination in a stoker, a retort, 30 extending across the front of the stoker, a series of hollow grate bars extending substantially at right angles to said retort, receiving the fuel discharged therefrom, and having air ports for delivering air into the fuel issuing from the retort, a tuyere box having a ported wall on which the fuel discharge ends of said grate bars are slidably mounted, ports in the bearing surfaces of the discharge ends of said bars registering with the ports in said ported wall to deliver air to the hollow interior of said bars, a primary air chamber communicating with and delivering air to said tuyere box, a secondary air chamber located immediately 45 below said grate bars and said retort and to which air is delivered from said grate bars, and means for delivering air from said secondary chamber to said fuel issuing from said retorts.
4. In combination in a stoker, a retort, 50 a plurality of grate bars extending substantially at right angles to said retort, their adjacent ends forming a wall of the retort, a tuyere box slidably supporting the far ends of said bars, each grate bar comprising a hollow member having air delivery ports formed in the retort end thereof, an air admission port formed in the opposite end and adapted to register with a cooperating portion of said tuyere box, and an air delivery port formed in the lower face of the bar intermediate the ends of the bar, a primary air chamber located below the grate bars of said stoker and communicating with
- said tuyere box, and a secondary air chamber 65 located between the primary air chamber and the grate bars and immediately below said grate bars, said secondary air chamber receiving air discharged from the ports in the lower face of said grate bars.
5. In a forced draft underfeed stoker furnace, a retort, hollow grate bars extending at substantially right angles to the retort, a discharge mechanism at the lower end of the bars, air delivery ports formed in the 70 front end walls of said bars for delivering air across the mouth of the retort, means adjacent the rear ends of the bars for delivering air to the discharge mechanism, air delivery ports located intermediate the 75 ends of said bars, and means for delivering major portion of the air entering the combustion chamber of the furnace through the hollow grate bars.
6. In a forced draft stoker, an underfeed 85 section, an overfeed section, an air admitting dump grate, and a tuyere box supporting the overfeed section and adapted to supply air to said overfeed section and dump grate, the overfeed section comprising a plurality of 90 hollow grate bars, said bars adapted to receive air from the tuyere box and deliver the same to the underfeed and overfeed sections.
7. The combination with a stoker having a primary air chamber at the discharge end of 95 the grate, a dump grate chamber at the rear of the primary chamber, a secondary chamber communicating with the fire box, of a grate having a plurality of hollow grate bars, each bar having an air admission port 100 communicating with the primary chamber, a delivery port at the center of each bar opening into the secondary chamber, and a hollow dump grate having air admission ports communicating with the primary chamber 105 and the delivery ports along the upper side thereof.
8. The combination in a stoker furnace having a tuyere box at the discharge end of the grate and an air chamber beneath the 110 grate, of a grate having a plurality of hollow grate bars, each bar having an admission port communicating with the tuyere box and delivery ports along the bar opening into the said air chamber, each bar being 115 reduced in cross-sectional area along said delivery ports.
9. A stoker comprising a retort formed by interchangeable retort bodies provided with fuel admission passages and constituting a 120 front wall of the retort, a series of grate bars for receiving fuel from the retort, the sides of the bars constituting a rear wall of the retort, an inclined table upon which said bodies and said bars are mounted, and means 125 for feeding fuel through said passages into said retort.
10. A mechanical stoker for furnaces com-

- prising interchangeable retort bodies assembled to form a front wall of the stoker, each of said retort bodies having fuel admission passages therein, a table forming the bottom of a retort and on which said bodies are mounted, a plurality of interchangeable grate bars, each having one end mounted upon said table, the ends of the bars cooperating with said bodies and with said table
- 5 to form a retort extending across the front of the furnace, said bars extending from the retort toward the rear of the furnace, means for forcing fuel through the fuel admission passages and means located at the front of the furnace for actuating said fuel feeding means.
- 10 11. In combination with the fuel feeding mechanism of a stoker, a drive shaft, a two part gear mounted on said shaft and comprising a hub portion rigidly mounted on the shaft and a toothed member rotatably mounted on said shaft, a shearing key between said hub and said toothed member,
- 15 and an operative connection between said toothed member and said fuel feeding mechanism.
12. In combination in a progressive feed stoker, a retort, a plurality of inclined hollow reciprocating grate bars provided with inlet passages and arranged to receive fuel from the retort, a twyer box supporting the lower ends of the grate bars, air passages in the twyer box cooperating with said inlet passages in the grate bars, respectively, and a plurality of delivery openings along the bottom of each bar, the flow area within each bar being successively decreased in cross-sectional area between the delivery openings from the first to the last of said
- 20 25 30 35 40
- In testimony whereof, I have hereunto subscribed my name this 19th day of May, 1917.

CHARLES F. MILLER.
